CONTROL DEVICE FOR ELECTRIC ALARMS

Joseph Lemire, Henri Lemire, and Rodolphe Lemire, Drummondville, Quebec, Canada, assignors of one-half to Norbert Boisvert, Drummondville, Quebec, Canada

Application May 26, 1938, Serial No. 210,218

1 Claim. (Cl. 200—54)

The present invention pertains to a novel device for controlling and governing the operation of an electric alarm.

The principal object of the invention is to provide such a device adapted to be mounted on a structural member that vibrates when a forcible entry is attempted. Such a member may be, for example, a window sash, window or door, or the frame or surrounding structure associated with a window or door. In general, the device of the invention embodies a pair of contacts carried by the vibratory member and governing the circuit to the alarm. One of these contacts is adapted to vibrate relatively to the other when the structural member vibrates. The vibratory contact is made relatively movable by suitable means such as a vibratory support, a weight or both. Where a resilient support is used, the invention also employs means for adjusting the tension of the support.

In one form of the invention, the control device is enclosed in a casing carried by the vibratory member and carrying one of the contacts. The other contact is carried on a spring arm attached to but insulated from the casing. The arm is also weighted to introduce a difference of inertia between the contacts, so that movement of the structural member introduces relative vibration between the contacts, with the result that the alarm circuit is rapidly made and broken.

Ordinarily, the contacts are normally in engagement with each other, and the alarm so constructed that it is idle in this condition but operates when the contacts separate. Obviously, these conditions may be reversed, but in either case the alarm operates when one of the contacts vibrates relatively to the other.

The invention is fully disclosed by way of example in the following description and in the accompanying drawing, in which

Figure 1 is a horizontal section, partly in elevation, of the device as applied to solid window frames or walls;

Figure 2 is a vertical elevation thereof;

Figure 3 is a vertical section of a window sash, showing in elevation a modified form of the invention applied thereto;

Figure 4 is a section on the line 4—4 of Figure 3;

Figure 5 is an elevation of the upper end of the device shown in Figure 3, and

Figure 6 is a detail, partly in section, of the lower end.

Reference to these views will now be made by 55

use of like characters that are employed to designate corresponding parts throughout.

In Figure 1, the numeral 1 designates a structural member which may be a portion of a wall or window frame. In any case, it is a member that is likely to be subjected to vibration if a forcible entry is attempted.

The device includes a suitable bracket 2, conductive of an electric current, to which is secured one end of a very light piece of sheet metal 3. The free end of the member 3 is secured to the center of a weight 4 as shown more clearly at the numeral 5 in Figure 2. The assembly is enclosed in a suitable casing 6 which is also conductive of electricity. The adjacent face of the weight 4 carries a contact 7 normally engaging a pointed contact 8 on the inner wall of the casing.

The bracket 2 is insulated from the casing 6 by an insulating insert 9. This member and the metal piece 3 are secured to the bracket 2 by rivets 10. The same rivets hold one end of a soft metal sheet 11 adapted to engage the member 1. By adjusting the bend of this sheet, the displacement of the weight 4 can be regulated.

A conductor 12 is connected to the bracket 2 by a screw 13. Similarly, another conductor 14 is fastened to the casing 6 by a screw 15. Both screws extend into the member 1 and may serve to support other parts of the assembly as clearly illustrated in Figure 1.

A circuit is thus made through the contacts 7 and 8 to an alarm. The contacts are normally in engagement with each other, and the alarm is one that is inoperative when these contacts are in engagement.

When a forcible entry is attempted at or near the member 1, the latter will be caused to vibrate. The weight 4 will also be set in vibration but at a slower rate because of its inertia. Consequently a separation, or repeated separations, of the contacts 7 and 8, will occur, opening the circuit and operating the alarm.

The modification shown in Figures 3, 4, 5 and 6 is designed for application to a movable window frame or sash. The frame member 20 carries a screw 21 which, in turn, preferably carries a bushing 22. Wire conductors 23 and 24 are suspended from the screw, the member 23 carries a weight 25 at its lower end, while the member 24 has its lower end bent and pointed at 26 and engaging in a socket 27 formed in the adjacent face of the weight 25. The upper ends of members 23 and 24 are wound around an insulating sleeve 28 fitted on the bushing 22, as shown more clearly

in Figure 4. Plates 29 and 30 are mounted on the sleeve 28 in engagement with the conductors 23 and 24 respectively and are held apart by an insulating disc 31. A similar disc 32 engages the coiled end of conductor 23, and suitable washers 33 are mounted on the bushing 22 to take up the slack.

Conductors 34 and 35 are fastened to the plates 29 and 30 respectively, whereby a circuit is made through the lower ends of the members 25 and 26. 10

When an attempt is made to force the window open, the vibration separates the contacts 25 and 26 and thereby causes the alarm to operate.

Bent plate 40 placed close to window frame 20 permits to regulate the contacts by turning screw 21. Plate 40 engaging frame 20 at a point offset 15 of the screw 21 causes the tilting of contacts 23 and 24 towards the glass forming part of member 20.

Although specific embodiments of the inven- 20

tion have been illustrated and described, it will be understood that various alterations in the details of construction may be made without departing from the scope of the invention, as indicated by the appended claim.

What we claim is:

A control device for an electric alarm comprising a pair of contacts suspended from a relatively vibratory structure, one of said contacts being weighted and in contact with the other of said contacts whereby vibration of said structure breaks the circuit, a bent plate at the suspension ends of said contacts and adapted to engage said structure, and a screw passed through said suspension ends and adapted to press said bent plate against the said structure in order to adjust the tension of said contacts.
